UNITED STATES PATENT OFFICE

148,959

DESIGN FOR A SALAD DISPENSER

Matthew E. Ryan, Chicago, Ill.

Application August 29, 1946, Serial No. 132,946

Term of patent 14 years

(Cl. D52—2)

To all whom it may concern:

Be it known that I, Matthew E. Ryan, a citizen of the United States, residing at Chicago, county of Cook, and State of Illinois, have invented a new, original, and ornamental Design for Salad Dispenser, of which the following is a specification, reference being had to the accompanying drawing, forming a part thereof, in which—

Fig. 1 is a top plan view of the salad dispenser, showing my new design;

Fig. 2 is a side elevational view thereof;

Fig. 3 is a front elevational view thereof;

Fig. 4 is a perspective view thereof.

I claim:

The ornamental design for a salad dispenser, as shown.

MATTHEW E. RYAN.
